UNITED STATES PATENT OFFICE.

EMIL TYDEN, OF EVANSTON, ILLINOIS.

ACCELERATOR FOR DRY-PIPE SPRINKLER SYSTEMS.

Application filed August 23, 1924. Serial No. 733,667.

The purpose of this invention is to provide an improved construction in a device of the nature of an accelerator for the action of the valve of a dry pipe sprinkler system. 60
5 It consists in the elements and features of construction shown and described as indicated in the claims.

In the drawings:

Figure 1 is an elevation of the main valve 10 of a dry pipe sprinkler system and the initial section of its discharge pipe equipped with an accelerator device embodying this invention.

Figure 2 is a section through the accelerator at the line 2—2 on Figure 1.

Figure 3 is an enlarged detail of a portion of the device shown in Figure 2.

Figure 4 is an enlarged detail of another portion of the device shown in Figure 2.

20 Figure 5 is an enlarged detail of a third portion of the structure shown in Figure 2, all said enlarged details being sections in the same plane as Figure 2.

Figure 6 is a section at the line 6—6 on 25 Figure 2 on an enlarged scale.

Figure 7 is a detail sectional view showing a modification of the feature shown in Figure 4.

Figure 8 is an axial section of a fitting 30 interposed in the connection from the air pressure region of the system to the atmospheric pressure chamber of the main valve.

The structure shown in the drawings comprises the main valve of a dry pipe sprinkler system of which the body or casing is shown at A, the main valve at B seating on two seats, a^1 and a^2 , for affording differential pressure areas for the pressures operating on the said valve and providing an interseat chamber, a^3 , which in the usual and familiar construction of this type of devices is normally under atmospheric pressure. The type and mode of action of this device as to the accelerating features consists in that 40 there is provision for admitting to the interseat or atmospheric pressure chamber pressure from the air pressure region of the system upon fall of pressure in said region which may result from the opening of the 45 sprinkler head, the admission of said pressure to the interseat chamber having the effect of opening the main valve promptly as soon as such fall of pressure occurs from the cause mentioned which makes it important 50 that the water should arrive quickly at the open sprinkler head. The pressure from

the air pressure region of the system is led to the interseat or atmospheric pressure chamber by way of the pipe, 1, which leads from the upper portion of the valve body 60 (which is in the air pressure region) by way of the accelerator device, D, to which the pipe, 1, leads, and the pipe, 2, which leads from the accelerator device to a fitting, 4, and the pipe, 3, from said fitting opening 65 into the interseat chamber as seen at 4^a. The fitting, 4, incidentally accommodates the drainage of water from the interseat chamber by way of the pipe member, 3, and otherwise has no direct relation to the subject matter of this invention. The construction of the accelerator device indicated in its entirety and as to its casing by the reference letter D, is for convenience mounted by means of bracket clamp, D¹, on the initial 70 pipe member, C, of the sprinkler system.

This accelerator device comprises a casing having two chambers, 10 and 11, with which the air pressure region of the system communicates, as hereinafter more particularly 80 described, by way of passages, 12 and 13, in said casing branching from an initial duct or port, 14, which is connected with and forms a part of the passage through a valve fitting member, E, more particularly hereinafter described in respect to its passages, valve seats and valves. The chambers, 10 and 11, at the side of the casing, D, opposite the valve fitting, E, have each an aperture in the outer wall, the aperture in the wall 90 of the chamber, 10, being a small one shown at 15, that in the chamber 11, being a large one shown at 16, and upon this outer wall of the casing, D, there is applied a cap, F, having in its applied face a large cavity, 17 95 with its large aperture registering with the aperture, 16, in the wall of the chamber, 11, and having a small aperture, 18, registering with the aperture, 15, in the wall of the chamber, 10. A duct, 19, connects the cavity, 17, with the aperture, 18. In the cavity, 17, there is mounted a diaphragm casing comprising two members, 20 and 21, between which a flexible diaphragm, 22, is clamped by its periphery. The diaphragm casing member, 21, has apertures, 22^a, for communication of the diaphragm chamber at one side of the diaphragm through the duct, 19, with the chamber, 10, and the diaphragm casing member, 20, has apertures, 20^a, for communication of the diaphragm chamber at the other side of the diaphragm 100 105 110

with the chamber, 11. It will be seen that the diaphragm, 22, constitutes in effect an imperforate partition separating the two chambers, 10 and 11, so far as air communication between them is concerned, but subject to the communication of pressure from the one to the other by virtue of the pressures which reach the opposite sides of the diaphragm through the respective apertured diaphragm casing members. In the diaphragm casing at the side toward the chamber, 11, there is mounted a plunger, 24, having an expanded head, 25, for seating on the diaphragm, the plunger itself obtaining bearing and guidance in a bearing, 20^b, with which the diaphragm casing member, 20, is provided at its center projecting into the chamber, 11. The end of the plunger protrudes from said bearing for encounter with the inner end of an operating member, 30, which as hereinafter more particularly described, extends air-tight through the wall of the chamber, 11, for a function herein-after more particularly explained.

The valve fitting, E, is cored and bored from end to end for mounting the valve seats and accommodating the valves and forming the passages which will now be described. Into the upper end of the fitting which is bored and counter-bored and interiorly threaded for the purpose, there is inserted a sleeve, 31, having a flange, 32, stopped upon the shoulder, 33, of the valve fitting, E, which is formed by counter-boring for that purpose, the sleeve being threaded below the shoulder and screwed into the bore of the fitting, E, below said shoulder. The upper end of this sleeve is slightly reduced in diameter and the aperture through which it is inserted is closed by a hollow cap, 35, into whose cavity the upper reduced end of the sleeve, 31, protrudes with clearance around it for free passage of air, for which purpose also lateral ports, 31^a, are provided. The lower end of the sleeve, 31, constitutes a seat for a valve, 40, having a stem which extends up through the sleeve and obtains guidance in the upper end or head of the sleeve through which it extends loosely enough to allow free passage for air independently of the ports, 31^a, a spring, 41, being provided coiled around the stem and reacting between the upper shoulder of the valve member and the head of the sleeve for normally holding the valve downwardly off its seat at the lower end of the sleeve and onto a seat, 43, which is formed around a port, 44, in the fitting, E. The valve member, 40, it will be seen is thus in a chamber, 45, which is formed in the fitting between two seats at which said valve member seats alternatively. This chamber is most conveniently formed by boring the fitting laterally, the bore being closed at the outer end by a plug, 45^a. Below the seat, 43, there is formed in the fitting a second chamber, 46, bounded at its lower side by an annular partitioning boss, 47, below which there is a valve seat, 48, for seating a valve, 50, whose stem, 51, extends up through the aperture 70 in said partitioning boss, 47, and across the chamber, 46, and through the port, 44, of the valve seat, 43, for the lower side of the valve, 40, for encounter with the lower end of said valve, 40, the dimensions of the parts being such that in the upward seating movement of the stem for seating the valve, 50, said stem encounters the valve, 40, and carries it off its seat and onto the opposite seat at the lower end of the sleeve, 31. The pipe, 1, is connected to the fitting, E, at the valve chamber, 45, as seen most clearly in Figure 6. From the valve chamber, 46, a passage, 46^a, leads up at the opposite side of the valve chamber, 45, from that at which the pipe, 1, is connected for connection with the pipe, 2, which at that point is connected to the fitting, E, for leading to the interseat atmospheric pressure chamber, a².

The purpose of certain details of the construction thus far described is to accommodate means for operating the double headed valve, 40, for its alternative seating, by means of connections with the diaphragm, 22, which means shall be accessible outside the casing or casings which enclose the various operating parts, in order that the operator or attendant may operate said valve at any time independently of the action of the diaphragm to test the condition of the parts and passages. For this purpose the stem, 51, of the valve, 50, is connected by a link, 51^a, with the short end of a weighted lever, 52, which is fulcrumed on a bracket arm, 53, of the casing, D, having its opposite end weighted for gravity movement in the direction to force the valve stem, 51, upward for seating the valve, 50, and unseating the valve, 40, from its lower seat and seating it at its upper seat at the lower end of the sleeve, 31. The weighted lever, 52, is constructed for being locked in upheld position holding the valve stem, 51, down and the valve, 50, unseated, and permitting the valve, 40, to be seated at its lower seat. The means for this purpose, and for releasing it to permit it to operate by gravity for reversing the valve positions as described, comprise the operating member, 30, above mentioned, which is pivotally mounted in the lower wall of the chamber, 11, through which wall it protrudes and is rendered air-tight at its protrusion through the wall by means of a flexible sleeve, 60, whose upper end is clamped tightly about an enlargement, 61, of said operating member while the lower end is similarly clamped about the boss, 62, around the aperture through which the said operating member protrudes from the casing. A convenient construction for this purpose is

that shown which consists of a plug, 65, which closes an aperture, 66, in the lower end wall of the chamber, 11, and which has at its upper inner side the boss, 62, mentioned upon which the lower end of the flexible sleeve, 60, is made fast, said plug, 65, being secured in position closing the aperture, 66, by a screwed-in follower, 70. This follower, 70, is apertured to admit the upper forked end, 80, of a weighted bell crank lever, 81, said lever constituting a latch member having its latch-nose, 82, engaging the flange, 75, which is formed at the lower end of the follower, 70, by counter-boring its upper end portion. This bell crank lever is fulcrumed near its angle on the weighted lever, 52, and has its horizontal arm quite heavily weighted as seen at 83 for effecting automatic engagement of the latch nose, 82, with the flange, 75, as described. Said end of the bell crank lever is engaged by the lower end of the operating member, 30, for disengagement of the latch nose by pivotal rocking of said operating member which occurs when its upper end is moved inward by the inward thrust of the plunger, 24, which results from the reduction of pressure in the chamber, 11, consequent upon the reduction of pressure in the air pressure region of the sprinkler system which may be caused by the opening of the sprinkler head. Such reduction of pressure, as already mentioned, occurs in the chamber, 11, immediately upon the opening of the sprinkler head, but is not experienced in the chamber, 10, because of the restricted communication between the two chambers due to the restriction which is afforded by a device, 90, shown in enlarged view in Fig. 4, and in modified position in Fig. 7, interposed in the passage, 12, leading to the chamber, 10. This device is itself not peculiar to this invention, being in a form which is quite familiar for like purposes, but which may be described, consisting of a sleeve, 91, counter-bored from its opposite end to an annular boss, 92, against which there is seated a metering disk 93, having a small aperture, 94. Into the opposite ends of the sleeve which is interiorly threaded there are screwed hollow plugs fitted at the inner end with strainers of finely perforated sheet metal or wire cloth for arresting solid matter which might otherwise clog the small aperture of the metering disk, 93.

The operation of this construction may be understood from the foregoing description to be as follows:

When the dry pipe valve and its connections are set up in the usual manner to be in readiness for operation upon the opening of the sprinkler head, with the proper degree of air pressure in the air pressure region of the system beyond the main valve, the air pressure obtains access by way of the pipe, 1, to both chambers, 10 and 11, and such access occurring during the accumulation of pressure by the air-compressing means pressure is communicated through the metering disk, 93, to the chamber, 10, as well as to the chamber, 11, through the free passage duct, 13; and pressure is thereby substantially equal upon both sides of the diaphragm, 22, causing both the diaphragm and the plunger, 24, to stand at normal position with respect to the chamber, 11, and to permit the operating member, 30, to stand in the position shown in Figure 2 in which it is normally held by the latch, 80, when the weighted lever, 52, is at latched position and in which it is also held normally by the flexible but normally straight tube, 60. At this position of the parts the valve, 50, is withdrawn from its seat and the valve, 40, is seated at its lower seat, 43, and unseated from its upper seat, 31^a, so that the pressure from the air pressure region of the system enters freely the fitting, E, and passing into the sleeve, 31, and out through the ports, 31^a, thereof, reaches both the chambers through the passages, 12 and 13, and the metering device, 90, as described. Upon reduction of pressure in the air pressure region such reduction is experienced promptly in the chamber, 11, but not promptly in the chamber, 10; and before such diminution of pressure is experienced effectively in the chamber, 10, the original full pressure in that chamber operates to flex the diaphragm in the direction for thrusting the plunger, 24, inwardly with respect to the chamber, 11, and against the upper end of the operating member, 30, causing this lower end to disengage the latch nose, 80, from the flange, 75, thereby releasing the weighted lever, 52, which falls and by its opposite end thrusting upwardly the valve stem, 51, seats the valve, 50, and unseats the valve, 40, from its lower seat and simultaneously seats it at its upper seat. This movement of the double headed valve, 40, opens communication through the pipes, 2 and 3, to the interseat or atmospheric pressure chamber of the main valve, and at the same time cuts off the access of said pressure to the chambers, 10 and 11. The admission of the air pressure under the main valve causes it to be completely opened without delay, for admitting the water to the sprinkler system. The seating of the valve, 40, at its upper seat cutting off communication from the sprinkler system to the casing, D, and both the chambers, 10 and 11, thereof, prevents the admission of water to the casing or any of the passages thereof and thereby obviates one of the inconveniences which has been experienced in the use of similar devices heretofore, resulting from the fact that the water which having entered these passages in the chambers is not easily cleared therefrom and tends to cause deterioration by 130

rusting and otherwise, and frequently causes clogging of the passages by solid matter carried in by the water; and this is the primary purpose of the feature of the construction described consisting in means for seating the valve, 40, to cut off the pressure communication with the casing when it is unseated to open pressure communication to the interseat atmospheric chamber of the main valve.

10 As noted above, and as seen in Figure 1, the pressure conveyed through the pipe, 2, reaches the interseat, or atmospheric pressure chamber, a^3 , of the main valve by way of the drainage pipe, 3, which leads from 15 said interseat chamber for draining the water therefrom into the drain connections seen at 3^4 . And it will be obvious that the effective transmission of said pressure to the interseat chamber, a^3 , requires the closing of 20 communication of the pipe, 3, with the drain, which is at atmospheric pressure. This is effected by providing in the fitting, 4, above mentioned, by which the pipe, 2, makes connection with the pipe, 3, a chamber having 25 in addition to connections with pipes, 2 and 3, an outlet to the drain, as seen at 4^d , and mounting in said fitting a valve, 4^b , carried by a lever, 4^c , fulcrumed for carrying the valve between the upper seat at 4^e , and the 30 lower seat at the drain port, 4^d , said lever being counterweighted as seen at 4^f , for seating the valve normally at said upper seat, from which it will be forced by the air pressure transmitted through the pipe, 2, to 35 the lower seat for closing the drain port, 4^d .

The modified construction shown in Figure 7, wherein the restricting device is shown located in a return bend pipe assembly leading out of and back into the casing for connecting the two chambers, 10 and 11, affords 40 facility for access to the restricting device for any attention which it may require, and at the same time offers the further advantage that the nipple containing the metering disk, 45 93 , may be kept thoroughly dry and the accumulation of moisture which would tend to rust the disk and clog the metering aperture, eventually stopping it up and defeating the function, being prevented by mounting 50 in heating proximity to said nipple any convenient means for keeping it warm, as an electric light bulb indicated at 97 .

It will be observed that the valve seat, 43 , for the valve, 40, is located in the chamber, 55 45 , below the level of both the inlet and outlet connection of that chamber with the pressure region of the system and with the atmosphere pressure chamber of the main valve respectively. The purpose of this arrangement is to form a water trap in which the valve seat, 43 , is situated.

This trap becomes filled with water when the main valve is initially opened for admitting water to the system, while the valve, 40, 60 is seated at its upper seat, 31^b , and the valve,

50, is seated at 48 ; consequently when the reverse movement occurs for seating the valve, 40, at its lower seat, said valve reaches that seat through the water so that the valve and seat are water sealed when the seating occurs. 70

I claim:—

1. In combination with a dry pipe sprinkler system and main valve thereof constructed for exposing differential areas to the air pressures respectively and having for that purpose at the water inlet side a chamber in which the pressure is normally substantially atmospheric, a passage leading from the air pressure region of the system to said chamber; an expandible and reducible device; means transmitting air pressure from said region of the system to different areas of a movable wall of said device in opposition to each other for determining a movement of the movable wall by the dominance of the pressure on one of said areas over that on the other area, said means comprising two passages affording unequal access for said pressure to said areas, respectively; two valve seats at which respectively the access of pressure from the air pressure region of the system to the atmospheric pressure chamber and to said areas of the expandible and reducible device is controlled; valve means positioned for moving between said two seats and connections operated by the moving wall of said device for shifting said valve means from one to the other of said seats. 90

2. In combination with a dry pipe sprinkler system and a main valve thereof constructed for exposure of differential areas to the air pressures respectively, and having for that purpose at the water inlet side, a chamber in which the pressure is normally substantially atmospheric; a passage leading from the air pressure region of the system to said chamber; an expandible and reducible device and a casing in which it is enclosed having a wall movable for such expansion and reduction; means transmitting air pressures onto different areas of said movable wall in opposition to each other for determining a movement of said wall by the dominance of the pressure upon one of said areas over that upon the other area, the wall of the casing having passages of different flow capacity leading to said different areas of the movable wall of said device, said passages being branched from a passage in common which constitutes the connection with the air pressure region of the system, said passage-in-common comprising a valve chamber and two valve seats therein at ports of communication for air pressure access to said passage-in-common and to the atmospheric pressure chamber of the main valve; a valve for controlling alternatively the two pressure accesses, said valve being mounted 125 130

in said valve chamber for seating alternatively at one or the other of said two seats, and being accessible for operation through the port leading to the atmospheric pressure chamber.

3. In combination with a dry pipe sprinkler system and the main valve device thereof constructed for exposing differential areas to the water and air pressures respectively; a chamber in which the pressure is normally atmospheric; a passage leading from the air pressure region of the system to said chamber; an expansible and reducible device exposed to the air pressure from said region reaching different areas of the movable wall of said device in opposition to each other through two passages affording unequal access of the pressure to said two areas respectively; a casing in which said expansible and reducible device is contained and in which the two passages to its movable wall are formed having for a portion of the passage which affords the more restricted access for the air pressure a pipe leading out from and back into the casing; a flow-restricting device in the portion of said fitting between its two connections with the casing and heating means positioned proximate to said portion which is outside the casing for warming and thereby preventing accumulation of moisture in said flow-restricting device.

4. In combination with a dry pipe sprinkler system and the main valve device thereof constructed for exposing differential areas to the water and air pressures respectively; a chamber in which the pressure is normally atmospheric; a passage leading from the air pressure region of the system to said chamber; an expansible and reducible device exposed to the air pressure from said region reaching different areas of the movable wall of said device in opposition to each other through two passages and affording unequal access of the pressure to said two areas respectively; a casing in which said expansible and reducible device is contained; a valve which controls access of the air pressure to the atmospheric pressure chamber; connections from the moving wall of the expansible and reducible device for operating said valve for opening it comprising a weighted lever outside the casing connected with said last mentioned valve; latching means for upholding the lever in position for holding said valve closed; an operating member extending air-tight through the casing wall from a point inside the casing at which it is exposed to actuation by the movement of

the moving wall of said expansible and reducible device to a position outside said wall for engaging the latch for releasing the weighted lever upon movement of said moving wall out of normal position, the latch being weighted for its latching movement in the direction in which that movement actuates the operating member for forcing said moving wall back to normal position, and adequately for so forcing it.

5. A device for cooperation with a dry pipe sprinkler system and the main valve thereof comprising a casing, an expansible and reducible element in the casing and a valve for controlling the communication of the air pressure region with the atmospheric pressure chamber of the main valve, a weighted lever outside the casing and mechanical connections therefrom for opening said valve by the gravity movement of the lever; a latch for engaging the lever with the casing to uphold the lever; an operating member extending air-tight through the wall of the casing and operatively related at its part inside the casing with the moving wall of the expansible and reducible device for being moved by the movement of the latter away from normal position, and at its part outside the casing operatively related to the latch for releasing the latter by the said movement of said operating member, the latch being mounted on the weighted lever and releasably engaging the casing to uphold the lever and permit it to drop upon being released from the casing.

6. In the construction defined in claim 5, foregoing, the latch being weighted for gravity movement to engage the casing and formed for engagement with the operating member in the lifting movement of the weighted lever and for disengagement from the operating member when the lever falls carrying the latch.

7. In an accelerating device for a dry pipe sprinkler system and the like, a valve which controls access of air pressure from the system to the main valve for accelerating the opening of the latter; a chamber in which said first mentioned valve obtains its seat, the chamber extending below said seat and having outlet to the main valve at a point wholly above the level of the seat, whereby there is formed a trap for water to seal the valve and its seat.

In testimony whereof, I have hereunto set my hand at Chicago, Illinois, this 21st day of August, 1924.

EMIL TYDEN.
